UNITED STATES PATENT OFFICE.

HENRY L. WALLACE, OF WALLINGFORD, CONNECTICUT, ASSIGNOR TO THE
R. WALLACE & SONS MANUFACTURING COMPANY, OF SAME PLACE.

DESIGN FOR A HANDLE FOR SPOONS, &c.

SPECIFICATION forming part of Design No. 31,733, dated October 31, 1899.

Application filed October 2, 1899. Serial No. 732,413. Term of patent 7 years.

To all whom it may concern:

Be it known that I, HENRY L. WALLACE, of Wallingford, in the county of New Haven and State of Connecticut, have invented and produced a new Design for the Handle of a Spoon and Similar Articles; and I do hereby declare the following, when taken in connection with the accompanying drawing and the letters of reference marked thereon, to be a full, clear, and exact description of the same, and which said drawing constitutes part of this specification, and represents a face view of a spoon-handle embodying my design.

As shown in the drawing, the leading or material feature of my design consists of a row *a* of small round beading extending upward on opposite sides of the handle. Outside the beading is a narrow rib *b*, which forms the edge of the handle and extending

entirely around the same terminates in scrolls *c* at the inner end. Inside the beading two long narrow ribs *g* extend from the inner end of the spoon toward the tip, where they terminate in scrolls *d*, and at the tip is a shell-like ornamentation *e*, the outer edge of which forms in appearance substantially a continuation of the beading. Between the inner ribs *g* is a blank panel *f*.

I claim—

The design for the handle of a spoon and similar articles as herein shown and described.

In testimony whereof I have signed this specification in the presence of two subscribing witnesses.

HENRY L. WALLACE.
